UNITED STATES PATENT OFFICE.

HARRY F. LEWIS, OF URBANA, ILLINOIS, AND HARRY D. GIBBS, OF SAN FRANCISCO, CALIFORNIA.

PROCESS FOR THE MANUFACTURE OF PHENANTHRAQUINONE.

1,288,431.

Specification of Letters Patent. Patented Dec. 17, 1918.

No Drawing.

Application filed January 10, 1918. Serial No. 211,165.

(DEDICATED TO THE PUBLIC.)

To all whom it may concern:

Be it known that we, HARRY F. LEWIS and HARRY D. GIBBS, citizens of the United States of America, and employees of the Department of Agriculture, residing in the city of Urbana, county of Champaign, State of Illinois, and in the city of San Francisco, county of San Francisco, State of California, respectively (whose post-office address is Department of Agriculture, Washington, D. C.) have invented a new and useful Process for the Manufacture of Phenanthraquinone.

This application is made under the act of March 3, 1883, chapter 143 (22 Stat. 625), and the invention herein described and claimed may be used by the Government of the United States or any of its officers or employees in the prosecution of work for the Government, or any person in the United States, without payment to us of any royalty.

Our invention relates to a process for the manufacture of phenanthraquinone from phenanthrene.

It is well known that phenanthraquinone is commonly produced by the oxidation of phenanthrene in an extremely fine state of division by means of chromic acid. In this process the steps necessary to obtain phenanthrene of sufficient purity are long and difficult, and furthermore, the chromic acid subsequently used for oxidation is a costly reagent. The object of our invention is to provide a process for the manufacture of phenanthraquinone which will be free from the objectionable features of the processes employed at present.

Our invention consists in the production of phenanthraquinone from phenanthrene by heating the phenanthrene until it passes into the vapor phase, mixing this phenanthrene vapor with an oxygen-containing gas mixture, forcing this mixture of gases into close contact with one or more of the finely divided oxids of the metals of the fifth and sixth groups of the periodic system, heating to a temperature ranging from 300° C. to 550° C. under which treatment the phenanthrene is partially oxidized to form the valuable product named.

To illustrate the practical operation of our process we shall describe in detail

the preferred procedure. Phenanthrene is melted and while kept in this condition it is mixed with air in excess of such an amount as is theoretically necessary to oxidize to phenanthraquinone whatever phenanthrene as is present in the current of air. The mixture of air and phenanthrene vapor is passed into a reaction chamber maintained at a temperature ranging from 300° C. to 550° C., the preferred temperature being 400° C. In this chamber the gas mixture is forced into close contact with one or more of the oxids of metals of the fifth and sixth groups of the periodic system, the pentoxid of vanadium is preferred, in the form of a fine powder. This powder is supported on trays or on a porous material where, by mechanical means, the current of mixed gases is forced over or through it. The gases are kept under pressure only sufficient to cause them to flow continuously through the reaction chamber. The products of the reaction, together with the unchanged phenanthrene, are condensed, and the phenanthraquinone is separated from the unchanged phenanthrene and other substances, if any, by known processes.

We have discovered that the process above described may be varied in a number of ways and yet will produce phenanthraquinone. Thus oxygen may be substituted wholly or in part for air, or air may be mixed with a gas which is relatively inert under the conditions obtaining in the process. The oxid of vanadium may be mixed with other substances such as asbestos, pumice stone, or other materials, and the oxids of molybdenum, tungsten, uranium may be employed. The gas mixture may be brought in contact with or forced through the catalyst in many ways. The proportion of phenanthrene to the oxygen-containing gas mixture may be varied within wide limits. And the reaction products may be separated by various well-known means.

Having thus described our invention, we claim—

1. A process for the manufacture of phenanthraquinone, which process consists in subjecting phenanthrene in the gaseous state and mixed with an oxygen-containing gas mixture to the action of the oxids of the

metals of the fifth and sixth groups of the periodic system, heated to temperatures ranging from 300° C. to 500° centigrade.

2. A process for the manufacture of phenanthraquinone, which process consists in subjecting phenanthrene in the gaseous state and mixed with atmospheric air to the action of the oxids of the metals of the fifth and sixth groups of the periodic system, heated to temperatures ranging from 300° C. to 500° centigrade.

3. A process for the manufacture of phenanthraquinone, which process consists in subjecting phenanthrene in the gaseous state and mixed with an oxygen-containing gas mixture to the action of the oxids of the metals of the fifth and sixth groups of the periodic system, heated to temperatures ranging from 300° C. to 600° centigrade.

4. A process for the manufacture of phenanthraquinone, which process consists in subjecting, while in the gaseous state and mixed with an oxygen-containing gas mixture, phenanthrene, together with other substances derived from coal tar, to the action of the oxids of the metals of the fifth and sixth groups of the periodic system, heated to a temperature of 300° C. to 600° centigrade.

5. A process for the manufacture of phenanthraquinone, which process consists in subjecting phenanthrene in the gaseous state and mixed with an oxygen-containing gas

mixture to the action of pentoxid of vanadium, heated to temperatures ranging from 300° C. to 500° centigrade.

6. A process for the manufacture of phenanthraquinone, which process consists in subjecting phenanthrene in the gaseous state and mixed with atmospheric air to the action of the pentoxid of vanadium, heated to temperatures ranging from 300° C. to 500° centigrade.

7. A process for the manufacture of phenanthraquinone, which process consists in subjecting phenanthrene in the gaseous state and mixed with an oxygen-containing gas mixture to the action of the pentoxid of vanadium, heated to temperatures ranging from 300° C. to 600° centigrade.

8. A process for the manufacture of phenanthraquinone, which process consists in subjecting, while in the gaseous state and mixed with an oxygen-containing gas mixture, phenanthrene, together with other substances derived from coal tar, to the action of the pentoxid of vanadium, heated to a temperature of 300° C. to 600° centigrade.

In testimony whereof, we affix our signatures in the presence of two subscribing witnesses.
